UNITED STATES PATENT OFFICE.

JOSEPH OLMSTED, OF KNOXVILLE, ILLINOIS.

IMPROVEMENT IN ELECTRO-MAGNETIC CAR-BRAKES.

Specification forming part of Letters Patent No. 98,880, dated January 18, 1870.

To all whom it may concern:

Be it known that I, JOSEPH OLMSTED, of Knoxville, in the county of Knox and State of Illinois, have invented certain new and useful Improvements in Electro-Magnetic Car-Brakes, of which the following is a full, clear, and exact description, reference being had to the accompanying drawing making part of this specification, and in which-

Figure 1 represents a plan or top view of a car-truck, partly in section, with my improvements attached; and Fig. 2, a vertical section through a portion of the same at the line *x x* of Fig. 1.

The nature of my improvements consists in dispensing with all toothed gearing as used in my invention patented April 27, 1869, and substituting therefor a simple friction-roller, whereby the friction and noise, as well as the expense of construction, are greatly lessened, while the proper action of the brake is secured by the direct agency of the wheels of the car or truck.

In the drawing, *A* is the frame of a car-truck; *a a* are the wheels, and *A¹ A²* are the axles. *B* is a horizontal shaft having a bearing, *b*, at one end loose enough to allow a slight amount of lateral play to the opposite end, which has its bearing in a sliding journal-box, or, as shown in the drawing, in the end of a swinging arm, *B'*, pivoted to the truck-frame. The shaft carries a friction-roller, consisting of a brass or copper plate, *C*, flanged, as shown, and having a hub, *c*, through which the shaft *B* passes, so as to allow the roller *C* to turn freely upon it. The freedom of the end of the shaft *B* at the swinging arm *B'*, or its equivalent, permits the flanged face of the roller to be always in contact with the axle *A¹*, so as to be rotated by it while the truck-wheels are revolving. The disk or friction-plate *D* is firmly secured upon the shaft *B*, near the roller *C*, and carries two electro-magnets, *d d*, the poles of which pass through it, and are made flush with its surface on that side which is adjacent to the roller *C*, being properly insulated by plates *d¹* in the disk. Wires *d² d³* connect the coils of the magnets with a battery placed in any desired position upon the train, through the intermediation of collars *d⁴* upon the shaft *B*, which allows the same to be rotated without twisting the wires,

the general arrangement of the disk *D*, wires, and collars *d² d³ d⁴* being substantially the same as that in the brake already patented. An armature, *E*, in the form of a flat circular plate, less in diameter than the roller *C*, is placed loosely upon the hub *c* of the roller *C*, being provided with pins *e*, which enter corresponding holes in the plate of the roller, and thereby cause the two to rotate together, while at the same time end motion on the hub *c* is allowed to the armature *E*, so that it may approach the friction-plate *D* and be in contact with it when the circuit is completed at the battery, and at the same time revolve with the roller *C*, carrying the friction-plate *D* with it. The shaft *B* is connected, by a chain, *f*, to the upper end of the lever *F*, which is pivoted to the brake beam *G* of the axle *A¹*, and has its lower end connected, by a rod, *f'*, to the brake-beam *G'* of the axle *A²*. The brake-beams *G G'* carry brake-shoes, *g* of the ordinary construction.

The operation of the devices is as follows: While the train is in motion the roller *C* and armature *E* are rotated, by the axle *A¹*, around the shaft *B*, which is stationary, the electric circuit through the wires and magnets being open. When it is desired to apply the brakes the circuit is closed at the battery by means of a suitable key, and magnetism thereby developed in the magnets *d*, by which the armature *E* is attracted toward and held in contact with the friction plate or disk *D*. The armature *E*, continuing to rotate with the roller *C*, and being held in contact with the disk *D*, which is secured to the shaft *B*, imparts rotation to the latter, and, winding thereby the chain *f'* upon it, applies the brake-shoes *g* to the wheels *a*. The winding of the chain *f* on the shaft *B* draws the roller *C* so tightly against the axle *A¹* as to prevent it from slipping, and insure its revolution until the wheel is locked by the brake and ceases to turn. When the brakes are to be released the circuit is opened by the key, and the disk *D* and shaft *B*, thereby freed from their connection with the armature *E*, yield to the falling of the brake-shoes *g* from the wheels, and the parts are in proper position to repeat the operation when required.

Similar devices to those herein described are attached to each truck of the train, and

the wires are so connected to the magnets and battery that the circuit is opened and closed through the whole series simultaneously, thereby enabling the brakes of the entire train to be simultaneously applied and released, enabling the speed of the train to be checked without loss of time, and greatly reducing the liability to accident.

What I claim, and desire to secure by Letters Patent, is—

1. The combination of the axle A¹, friction-roller C, and armature E with the friction-plate D and magnets d d of an electro-magnetic battery, arranged and operated substantially as set forth, for the purpose of causing the plate D to be held in contact with the armature E, and revolve, to be released, and remain at rest, as desired.

2. The shaft B, supported at one end by the swinging arm B' or its equivalent, for the pur-

pose set forth, and the roller C, in combination with the chain f and lever F, substantially as shown and specified, to increase the pressure of the roller C against the axle A, and prevent it from slipping while the brakes are acting on the wheels.

3. The shaft B having lateral play at one end, for the purpose set forth, in combination with the friction-plate D, magnets d d, and wires d² d³ of an electro-magnetic battery, arranged and operated substantially as specified.

In testimony that I claim the foregoing as my invention I have hereunto set my hand this day of April, 1869,

JOSEPH OLIMSTED.
